OSCILLATING ELECTRIC FAN

Carl Buttner, Fulton, N. Y., assignor to The Hunter Fan & Motor Company, Fulton, N. Y., a corporation of New York

Application December 15, 1931, Serial No. 581,190

7 Claims. (Cl. 230—271)

This invention relates to electric fans of the type which includes a motor housing mounted on a base to have an oscillating movement and a fan mounted on the motor shaft, and has for its object a particularly simple and efficient mechanism for disconnecting the motor housing from the oscillating mechanism so that the fan remains in a fixed position and connectable at will so that the fan will oscillate when desired. It further has for its object a particularly simple, efficient and compact arrangement of the oscillating mechanism and the manual control therefor. It further has for its object a fan in which the fan housing is adjustable or tiltable into different angular positions about a transverse axis and means for holding it in its adjusted position combined with the manual control means for connecting and disconnecting the oscillating mechanism from the motor. Other objects will appear throughout the specification.

The invention consists in the novel features and in the combinations and constructions hereinafter set forth and claimed.

In describing this invention reference is had to the accompanying drawings in which like characters designate corresponding parts in all the views.

Figure 1 is a longitudinal sectional view through the fan housing and contiguous parts on the line 1—1, Figure 2.

Figure 2 is a rear elevation, partly in section, parts being broken away and a portion of the fan housing being omitted, taken approximately on the plane 2—2, Figure 1.

Figure 3 is a detail view of the portion of the motion transmitting mechanism between the motor shaft and the spindle of the base to effect the oscillation of the fan and is taken on line 3—3, Figure 1.

Figure 4 is an enlarged sectional view on line 4—4, Figure 2.

Figure 5 is an elevation of the operating member for the oscillating mechanism.

Figure 6 is an elevation looking to the left in Figure 5.

Figure 7 is an end view of the sleeve shown in Figure 4 in which the operating mechanism shown in Figures 5 and 6 is mounted.

Figure 8 is a detail view of the spindle section of the base.

11 designates generally a housing, 12 a motor of any suitable construction mounted in the housing and having a rotor or shaft 13, this extending to the outside of the housing and having a fan 14 mounted thereon in the usual manner. The

housing is mounted to oscillate on a suitable base, and this base, as here shown, consists of a lower section 15 and an upper section 16 pivoted thereto on a transversely extending axis. The lower section 15 may be mounted in vertical position on a shelf or the like or on an upright wall. The upper section is provided with a spindle 17 and a leaf or hinged portion 18 provided with a pivot bearing 19, the leaf extending between complementary leaves 20 on the lower base section 15, the leaves 20 being also provided with bearing openings. The sections 15 and 16 of the base are held in their adjusted or angular position as will be hereinafter described. The housing 11 is provided with a hub 21 swivelled on the spindle 17 and has its lower end located in a channel 22 at the base of the spindle for forming an oil-tight joint. The hub 21 depends from a lower or bottom section 23 of the housing 11. The upper section of the housing is the major part of the housing and is formed with supports for the motor and bearings for the motor shaft and for the motion-transmitting mechanism hereinafter described. The upper section is provided with a removable back cover portion 24.

The motion transmitting means for effecting the oscillation of the housing 11 relatively to the base or about the spindle 17 may be of any well known construction, that here shown comprising a worm wheel 25 mounted on the upper end of the shaft 26 which is journaled in a suitable upright bearing in the upper section of the housing 11, the worm wheel 25 meshing with a worm 27 on the motor shaft 13, a pinion 28 on the lower end of the shaft 26 meshing with a gear 29 mounted on a suitable spindle 30 and a link 31 located in the upper portion of the bottom section 23 and mounted at one end on the crank pin 32 on the lower side of the gear 29 and connected at its other end eccentrically to the spindle 17. The general form of this oscillating mechanism forms no part of this invention, which relates to the connecting and disconnecting of the mechanism into and out of motion transmitting relation to the housing.

As here illustrated, the connecting rod 31 is connected to the spindle through a clutch member or section 34 located at the upper end of the spindle 17 within the housing 23, the link being mounted on an eccentric pin 35 on the section or disk 34. The section or disk 34 has an axle 36 located in a coaxial bore 37 in the upper end of the spindle 17. Normally during the operation of the fan or the motor, the clutch section or disk 34 will oscillate idly but when clutched to the spin-

idle, the fan housing will oscillate. The means for clutching the section 34 to the spindle comprises a shiftable clutch section 38 in the form of a pin extending lengthwise of the spindle 17 5 and located in a suitable passage 39 therein. The pin 38 has a tapered point 40 at its upper end for entering a tapered hole 41 in the disk 34. The pin 38 is spring-pressed by a spring 42 so when the force holding it out of engaged position, is 10 released, the clutch section or pin 38 will move into engaged position, and if when released it is not in line with the hole 41, it will snap into the hole 41 when the hole 41 registers therewith during the idle oscillation of the disk 34. The pin 15 38 is provided with an extension extending crosswise of the bearing opening 19 of the spindle 16 to the base section 15.

The means for operating the clutch section 38 includes a member arranged coaxially with the 20 pivotal joint between the sections 15 and 16 of the base. The pivotal joint comprises a sleeve 45 extending into the bearing openings of one of the leaves 20 and the leaf 18, and having a stud 46 extending through the bearing opening in the other leaf 20, the sleeve having an annular collar or head 47 at its outer end, and a nut 48 threading on the stud against the contiguous leaf 20, the leaf and the nut being here shown as having coacting conical friction faces as at 49. Thus by 25 loosening the nut, the angle of the spindle portion can be varied relatively to the section 15 which is secured to the shelf or a wall.

The operating member for the clutch section 38, which, as before stated, is arranged coaxially 30 with this joint is here shown as a stud or spindle 50 extending into the bore of the sleeve 45 and having a handle or knurled head 51 at its outer end thrusting against the sleeve, the stud having gear teeth 52 at its inner end, which through an 35 opening 53 in the sleeve 45, engage with rack teeth 54 provided on the lower end portion of the clutch section 38. Thus by turning the operating member 50 in one direction, the clutch section 38 will be withdrawn out of engagement with the disk or clutch section 34 and upon the releasing of the handle the spring 42 is free to re-engage the clutch sections. In order to hold the clutch section in its retracted position, means is 40 provided for latching it in its retracted position. This latch means, as seen in Figures 4 and 5, is 45 a pin or shoulder 55 provided in the head or collar of the sleeve 45 and coacting with an inclined or cam-shaped tooth 56 provided on the opposing face of the head 51 of the operating member 50. The operating member has a limited endwise movement against the action of a spring for 50 frictionally or for impositively interlocking the pin 55 with the tooth 56 or for permitting the latching or ratcheting operation.

55 57 designates a spring which encircles a screw 58 extending axially of the operating member 50 and which threads into the stud 46, the spring being located in a suitable counterbore in the operating member 50 and thrusting at one end 60 against the head of the screw and at its other end against the bottom of the counterbore. The spring thus tends to thrust the operating member 50 inwardly or against the pin 55. There is a narrow notch 59 arranged on one side of the tooth 56 and a wide notch 60 on the other side of sufficient length to permit the operating member to turn while the spring 42 is reacting to carry the point 40 of the clutch section 38 into the opening 41 of the clutch section or disk 34.

70 75 The means for holding the housing 12 in any

one of a plurality of angular adjustments relative to the spindle 17 when the clutch section 38 is declutched from the section or disk 34, so that the fan may be permanently directed in any one of a number of angular directions, will now be 5 described. In the illustrated embodiment of my invention, the clutch section 38 is provided with a laterally extending shoulder 61 for coacting with any one of a series of internal notches 62 provided in the hub 21, these notches being located to receive the shoulder 61 when the clutch section 38 is in its retracted position and are also so located that the shoulder 61 is clear of the notches 62 before the point 40 enters the opening 41 in the section or disk 34. Hence by 10 turning the operating member 50 to let the spring 42 react sufficiently to carry the shoulder 61 out of engagement with the notches 62 but retaining hold of the operating member 50, so as not to permit the conical point 40 to enter the openings 20 41 of the section or disk 34, the housing 12 can be turned to any angle and the clutch section 38 again withdrawn against the action of its spring 42, carrying the shoulder into interlocking engagement with one of the notches 62 so that the housing is set to direct the fan at a certain angle. When the pin 61 clears the notches 62 it is located in an arcuate groove 63, the end walls 64 of which form stops for engaging the pin 61 and limiting the turning of the housing 11 so that the pin will not be shifted out of juxtaposition to the hole 41 or out of the range of the hole. This might happen if the housing 11 were turned by hand when the pin 61 was in the clearance 30 above the teeth 62 and no means as the stops 64 35 provided to limit the range of turning movement of the housing.

In order to limit the tilting movement of the section 16 relative to the base section 15 when the section 15 is mounted on a shelf or table, 40 one of the leaves 20 of the base section 15 is provided with a screw 70 having an end 71 which extends into a slot 72 in the leaf 18 of the spindle section 16, so that upon loosening of the nut 48 the spindle section and housing carried thereby cannot be tilted so far forwardly or rearwardly that the fan during the oscillation thereof will encounter obstructions. Likewise, when the base section is mounted upon a wall, the end 71 of the screw 70 enters a similar slot 73 to avoid 45 excessive tilting when the fan is mounted on the wall.

Owing to the housing and mounting thereof on the spindle, all the mechanism is located in an oil-tight housing. Owing to the shiftable clutch section 38 the fan can be made an oscillating fan or stationary fan at will and owing to the radial adjustment due to the shoulder 61 and the notches 62, the fan can be directed at any one of a plurality of fixed angles. Owing to the coaxial arrangement of the operating mechanism for the clutch section 38 with the joint between the sections of the base, the structure is particularly compact and economical in manufacture.

60 65 What I claim is:

1. In an electric fan, a base including upper and lower sections, the upper section being pivoted to the base to shift about a transverse axis, the upper section being formed with a spindle, a 70 housing having a hub journalled on the spindle, a motor mounted in the housing, a fan mounted on the motor shaft outside the housing, motion transmitting means between the motor shaft and the spindle to cause oscillation of the housing,

the motion transmitting means being located in the housing and including a shiftable clutch section for connecting and disconnecting the motion transmitting means and the spindle and an operating member for the shiftable section arranged coaxially with the transverse axis of the sections of the base.

2. In an electric fan, a base including upper and lower sections, the upper section being pivoted to the base to shift about a transverse axis, the upper section being formed with a spindle, a housing having a hub journalled on the spindle, a motor mounted in the housing, a fan mounted on the motor shaft outside the housing, motion transmitting means between the motor shaft and the spindle to cause oscillation of the housing, the motion transmitting means being located in the housing and including a shiftable clutch section for connecting and disconnecting the motion transmitting means and the spindle and operating means for the shiftable section including a member arranged coaxially with the transverse axis of the sections of the base, said operating means also including a member operable to tighten the joint between the sections of the base.

3. In an electric fan, a base including upper and lower sections, the upper section being pivoted to the lower section about a transverse axis, the section having lapping hinge leaves formed with bearing openings, a housing mounted on the upper section to oscillate about an upwardly extending axis, a motor mounted in the housing, a fan connected to the motor shaft outside the housing, motion transmitting means between the motor shaft and the upper section of the base to effect oscillation of the housing including a shiftable clutch section extending lengthwise of the axis of the upper section and crosswise of the pivotal axis between the sections, a sleeve extending through the bearing openings of the sections of the base and having a threaded stud at one end and a nut threading on the stud against the outer face of one of the leaves, the sleeves having an opening in one side, an operating member journalled in the sleeve and having a head at its outer end, said member and the clutch section having coacting means whereby upon turning of the operating member, the motion thereof is transmitted to the clutch section.

4. In an electric fan, a base including upper and lower sections, the upper section being pivoted to the lower section about a transverse axis, the sections having hinge leaves formed with aligned bearing openings, a housing mounted on the upper section to oscillate about an upwardly extending axis, a motor mounted in the housing, a fan connected to the motor shaft outside the housing, motion transmitting means between the motor shaft and the upper section of the base to effect oscillation of the housing including a shiftable clutch section extending lengthwise of the axis of the upper section and crosswise of the pivotal axis between the sections, a sleeve

extending through the bearing openings of the sections of the base and having a threaded stud at one end, a nut threading on the stud against the outer face of one of the leaves, the sleeve having an opening in one side, an operating member journalled in the sleeve and having a head at its outer end, said member and the clutch section having means coacting through said opening whereby upon turning of the operating member, the motion thereof is transmitted to the clutch section, a screw extending axially of the operating member and threading into the stud, and a spring interposed between the head of the screw and said member.

5. In an electric fan, a base including upper and lower sections, the upper section being pivoted to the base to shift about a transverse axis, the upper section being formed with a spindle, a housing having a hub journalled on the spindle, a motor mounted in the housing, a fan mounted on the motor shaft outside the housing, motion transmitting means between the motor shaft and the spindle to cause oscillation of the housing, the motion transmitting means including a shiftable clutch section for connecting and disconnecting the motion transmitting means and the spindle and an operating member for the shiftable section arranged coaxially with the transverse axis of the sections of the base.

6. In an electric fan, a base including upper and lower sections, the upper section being pivoted to the lower section about a transverse axis, a housing mounted on the upper section to oscillate about an upwardly extending axis, a motor mounted in the housing, a fan connected to the motor shaft outside of the housing, motion transmitting means between the motor shaft and the upper section of the base to effect oscillation of the housing including a shiftable clutch section extending lengthwise of the axis of the upper base section and operable to connect and disconnect the motion transmitting means and the upper base section, and an operating member for the shiftable clutch section arranged coaxially with the transverse axis of the sections of the base.

7. In an electric fan, a base including upper and lower sections, the upper section being pivoted to the base to shift about a transverse axis, the upper section being formed with an upwardly extending spindle, a support having a hub journalled on the spindle, a motor mounted on the support, a fan connected to the motor shaft to be rotated thereby, motion transmitting means between the motor shaft and the spindle to cause oscillation of the support, the motion transmitting means including a shiftable clutch section for connecting and disconnecting the motion transmitting means and the spindle, an operating member for the shiftable section arranged coaxially with the transverse axis of the sections of the base, and connections extending lengthwise of the spindle between the operating member and the shiftable section.
